Robert H. Crowle, Mount Prospect, and William G. Crowle, Deerfield, Ill., assignors to General Box Company, Des Plaines, Ill., a corporation of Delaware

Filed Mar. 12, 1962, Ser. No. 69,186

Term of patent 14 years

(Cl. D34—15)

The essential features of my design reside in a generally rectangular shaped, partially open body with a horizontal hood having an integral angular rectangular strip representing a wind shield projecting from the end adjacent the open portion, and at the other end a radiator representation that comprises a depression that is integral with the bumper portion, all as shown.

The side not shown is substantially the same as that shown, and the dominant features of my design reside in the portions shown in full lines.

We claim:

The ornamental design for a toy vehicle substantially as shown and described.
